UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,619, dated September 4, 1894.

Application filed August 3, 1894. Serial No. 519,372. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of connected ornamental panels formed of a series of scrolls 10 with flowers and leaves placed in the panels and small oval-shaped ornaments between each panel as represented in the accompanying drawing.

The border or upper portion of the design 15 is formed of ornamental panels containing flowers and leaves and scroll ornaments on each side of said panels, connected therewith

by ornamental scrolls and forming side panels, with flowers and leaves placed therein as shown in the drawing. The border is separated from the hanging by a narrow striped band as shown.

What I claim is—

1. The design for wall paper herein shown and described.
2. In the design for wall paper, the border herein shown and described.

Witness my hand this 31st day of July, 1894.

CHARLES BOOZE.
